PERFORATING MACHINE

Clarence J. Russnak, Chicago, Ill., assignor to
Teletype Corporation, Chicago, Ill., a corpora-
tion of Delaware

Application March 1, 1944, Serial No. 524,603

16 Claims. (Cl. 164—113)

The present invention pertains to perforating machines and more particularly to perforating machines for the preparation of signal control tapes.

In the use of certain types of perforating machines for preparing tape with code combinations perforated therein, it has been found that improper operation of the keyboard, such as releasing the key too quickly, results in an incorrect code being perforated in the tape. This is especially true of Wheatstone perforators, because in this type of perforating machine the operation of a key selects certain punch interponents, the upper ends of which are later moved by a punch hammer to cause the individual punches to perforate the tape. In the case of improper key operation it has been found that the selected punch interponents do not remain in their selected positions for a time sufficient for the punch hammer to move against them and cause actuation of the individual punches, but instead return to their normal position before the punch hammer is so operated. Such an occurrence results in improper, incorrect, or blank code combinations appearing in the tape, and inasmuch as the tape is later used to transmit the code messages over a printing telegraph system, it is clear that such errors result in communication errors.

The primary object of the present invention is to establish the selective setting of the punch interponents in a perforating device pending the completion of the perforating function.

Another object of the invention is to provide means to prevent the punch interponents from returning from their selected to normal positions before the punch hammer can be operated to an extent necessary to insure movement of the punch interponents against the punches.

The invention comprises a plurality of latches one individual to each of the standard T-levers of a Wheatstone perforator, the latches acting to lock a selected T-lever in its downward or selected position. A common bail is provided which is connected through a linkage system to a bell crank lever operating from the punch head operating solenoid. The punch interponents are held, through the latches, in their selected position during a major portion of the punch hammer stroke and are then released through the action of the bail during the latter part of the stroke of the punch hammer.

A more detailed understanding of the invention may be had from the following description

with reference to the accompanying drawings, in which:

Fig. 1 is a plan view, partly broken away, of the apparatus embodying the invention;

5 Fig. 2 is a sectional view taken approximately on the line 2—2 of Fig. 1;

Fig. 3 is a rear elevational view of the apparatus disclosed in Fig. 1; and

10 Fig. 4 is a sectional view taken approximately on the line 4—4 of Fig. 1.

In describing the mechanism embodying the invention, it is first necessary to generally describe the Wheatstone perforator and its operation, inasmuch as it has been chosen as the apparatus on which the present invention will be disclosed. However, it is to be understood that the use of the apparatus embodying the invention is not limited merely to use with a Wheatstone perforator, but may be used with any other 15 tape perforator having a similar difficulty to be overcome.

For a complete description of the Wheatstone perforator attention is directed to U. S. Patent No. 1,085,985, issued to E. E. Kleinschmidt on 20 February 3, 1914, or to "Teletype" Bulletin No. 125, issued in August, 1937, by the Teletype Corporation, Chicago, Illinois.

25 Referring to Fig. 2, the apparatus comprises a bank of key levers 11, the keys of which are provided with the characters of a universal keyboard. The key levers 11 are all fulcrumed about a transverse bar 12, at their inner ends. Arranged longitudinally of and beneath each of the key levers 11 are a plurality of code bars 13, each secured to an individual key lever 11 by means of a connecting link 14. The code bars 13 extend rearwardly in the apparatus and are all fulcrumed near their inner end about a transverse bar 16. The individual notched code bars 13 each have a spring 17 at their inner extremity, which normally tends to pivot the code bar 13 about the fulcrum 16 in a counterclockwise direction, as viewed in Fig. 2.

30 Arranged beneath the lower surface of the notched code bars 13 are a plurality of twenty transversely extending T-levers 18, as may be more clearly seen in Fig. 4. The T-levers 18 are supported by parallel links 19 pivoted to the 35 downwardly extending legs of the T-levers 18, the parallel links 19 being pivoted on a bracket 21 secured to the frame of the machine. The parallel connecting linkage has been provided so that the T-levers 18 will always move in a vertical direction despite which T-lever 18 is selected by a code bar 13. In this way there will

be no tilting of a depressed T-lever 18, especially when moved by one of the notched code bars 13 which may be toward the right or left side of the machine.

A plurality of rearwardly extending levers 22, which are also fulcrumed about the point 16 and which are normally biased in a counterclockwise direction by means of individual springs 23, connect nineteen of the twenty T-levers 18 to a connecting link 24. The connecting link 24 forms 10 the lower extremity of the punch interponents, which comprise the link 24, an adjustable connecting rod 26 immediately above, and the punch interponent member 27. It is to be noted that reference above was made to only nineteen of the twenty T-levers being connected through the rearwardly extending levers 22 to the punch interponents 27. The twentieth of the T-levers 18 is connected by means of a rearwardly extending lever, such as 22, to control an electrical contact 28 which is utilized for a purpose to be described later. The rearwardly extending lever 22 which controls the electrical contact 28 is connected to a universal T-lever 18 which is caused to be selected upon the depression of each of the key levers 11.

In operation, the depression of a key lever 11 causes its associated code bar 13 to be pivoted in a clockwise direction, Fig. 2, about the point 16, which in turn depresses certain of the T-levers 18 depending on the specific configuration of the underside of the code bar 13. The depression of the selected T-levers 18 results in the rearwardly extending levers 22 being fulcrumed about the point 16, against the tension of their associated springs 23, resulting in the links, adjustable rods, and punch interponents 27 being raised upwardly, as viewed in Fig. 2. The upward movement of the interponents 27 places them in their selected position, at which point their upper extremity lies adjacent to a plurality of punches 29, one of which is individual to each of the punch interponents 27. Upon the release of the key lever 11, the code bar 13 and key lever tend to move in a counterclockwise direction, as viewed in Fig. 2, under the tension of the individually associated springs 17. The T-levers 18 which have been selected also tend to move to their normal or upward position under the tension of the individual springs 23 which impart a counterclockwise movement to the rearwardly extending levers 22 which connect directly to the T-levers 18. This, of course, would result in the downward movement of the punch interponents 27 to their normal positions. The downward movement of the code bars 13 and key levers 11 is limited by means of a stop 31, whereas the upward movement of the key levers 11 is likewise limited by means of a transverse leather member 32 which is secured within the frame of the machine and overlies all of the key levers 11 toward their front extremity.

Referring to Fig. 2, it might be noted that the punch interponents 27 are formed in two separate rows, one of which comprises ten interponents while the second comprises nine. In a like manner, the punches 29 are divided into two tiers, the upper of which comprises ten punches, one individual to each of the ten interponents 27 in the one row, whereas the lower tier of nine punches is individual to the row of nine interponents. The two rows of punches 29 are separated by a row of punches 33 which operate to perforate a central line of perforations in the tape which are utilized to feed the tape. The

individual punches 29 are formed with shoulders 34 separated by a central reduced section 36.

Referring to Fig. 1, a punch head or hammer 37 is reciprocably mounted within the guides 38, and is normally urged to a rearward position by means of the spring 39. As disclosed in Fig. 2, upon the forward movement of the punch hammer 37 the punch interponents 27 will be engaged by its forward edge, causing them to abut against their individual punches 29, resulting in the punches being forced through the tape which normally passes through the tape guide or opening 41 provided therefor. A comb 42 is connected to the operating punch head 37 and moves therewith. Said comb has slots therein through which pass the reduced section 36 of the punches 29. After the punches have been operated to perforate the tape, and when the punch hammer 37 starts its return movement, the comb 42 will engage the front surface of the rear shoulders 34 of the punches 29, thereby insuring that the punches will be positively removed from their perforations in the tape. A chad chute 43 has been provided to remove the tape punchings away from the perforating mechanism.

Referring to Figs. 1 and 2, an operating lever 44 is provided which is pivoted at 46 and is normally urged in a counterclockwise direction by means of the spring 47. One end of the operating lever 44 has a pin 48 extending therefrom by means of which the operating lever 44 is connected to a bell crank 49. The bell crank 49 is pivoted at a point beneath the pin 48 and has its opposite end connected to an armature 51 which is under the control of a solenoid 52 (Fig. 3). The operating lever 44 has a lug 53 extending vertically therefrom through which is positioned a set screw 54 which is adjacent to and aligned with the rear surface of the punch hammer 37.

In operation, upon the solenoid 52 becoming energized due to the closing of the electrical contact 28 by means of the universal T-lever 18, a circuit is established for the energization of the solenoid, and the armature 51 will be drawn within the solenoid. The downward movement of the armature 51 causes the bell crank 49 to pivot, resulting in the operating lever 44 being moved in a clockwise direction as viewed in Fig. 1, against the tension of its spring 47. Such a movement 40 to the operating lever 44 results in the set screw 54, which is associated with the lug 53 of the operating lever, engaging the punch hammer 37 and causing the punch hammer 37 to be moved forwardly against the tension of its spring 39. The movement of the punch hammer 37, under the force of the operating lever 44, results in the punch interponents 27 being moved toward the right, as viewed in Fig. 2, and impinging upon their associated punches 29 resulting in the tape being perforated. It is to be remembered, however, that only those interponents 27 which have been selected and have been moved upwardly will actuate their individual punches 29. The other interponents 27 which have not been selected and moved upwardly will be moved forwardly by means of the punch hammer 37 but, inasmuch as they have not been raised to a point opposite their individual punches 29, will not operate the punches to perforate the tape. Special means are provided to insure the operation of the punches 33 which perforate the tape feed holes.

Inasmuch as the key levers 11 are held depressed only momentarily, the associated code levers 13, T-levers 18, and rearwardly extending

levers 22, are likewise actuated only momentarily. This is also true of the universal T-lever 18 which controls the electrical contact 28 for the energization of the solenoid 52. Immediately after the key lever 11 is released, the rearwardly extending lever 22 controlling the electrical contact 28 will be caused to pivot in a counterclockwise direction, as viewed in Fig. 2, by its individual spring, resulting in the electrical contact 28 being opened. As such an opening of the contact will result in the breaking of the electrical circuit for the solenoid 52, the solenoid will become de-energized and release its armature 51 to move upwardly, as viewed in Fig. 3. Any such upward movement of the armature 51 results in a pivoting of the bell crank 49 and a resultant counterclockwise movement to the operating lever 44 both under positive movement of the pin 48 and the contraction of the spring 47. Such a movement of the operating lever 44 will allow the punch hammer 37 to move rearwardly under the force of its associated spring 39, resulting in the punches being removed from the perforations in the tape through the action of the comb 42. The perforating machine is now in condition for the depression of a subsequent key lever 11 to set up a new code combination for perforating the tape.

It is to be remembered that the depression of the key lever 11 not only caused the interponents 27 to be moved to a selected position, but also caused the energization of the solenoid 52 and the resultant operation of the punch hammer 37 through the mechanical linkage system. In the event that the operator removes his or her finger from the key of the key lever 11 too quickly there is a tendency for the punch interponents 27 to be moved to their upward position and then drop back to the normal position before the punch hammer 37 is caused to be moved inwardly, as viewed in Fig. 1, to move the punch interponents 27 against the individual punches 29. If this occurs, an incorrect code combination will be perforated in the tape. In order to overcome this disadvantage the present device embodying the invention has been designed, to assure that the punch interponents 27 will remain in their selected position for a length of time sufficient to allow them to be engaged by the forward surface of the punch hammer 37.

Referring to Figs. 2 and 3, it may be seen that a rod 56 is connected to the bell crank lever 49 which rod has its opposite end connected to a downwardly extending link 57 (Figs. 2 and 3). The lower extremity of the lever 57 terminates in a connection to a bell crank lever 58, as shown in Fig. 2. It is to be noted that this junction is made through a slot 77 in the lever 57. The bell crank lever 58 is pivoted at 59 to a bracket 61 extending from the frame of the machine. The lower extremity of the depending arm of the bell crank lever 58, as viewed in Fig. 2, is connected to a forwardly extending link 62 which has a twist therein to cause the lever to change its form through 90 degrees. The forward extremity of the link 62 is pivoted to a bell crank 63 which is disclosed more fully in Fig. 1 in dotted lines. The bell crank 63 is pivoted at 64 to a pin extending from the frame and has its opposite extremity pivotally secured to a link 66. The link 66 is also formed of such a configuration that it is twisted through 90 degrees, and is connected at its leftward end, as viewed in Fig. 4, with a bell crank 67 which is pivoted to a transversely extending rod 68. The opposite end of the bell crank lever

67 is formed of a transverse bail 69, as may be better seen in Fig. 1. The bail 69 extends for some distance and has its opposite extremity also pivoted to the rod 68.

Referring to Fig. 4, a bell crank 71 is pivoted on a rod 72 and is normally urged in a clockwise direction by means of a spring 73. The apparatus is provided with nineteen of the individual bell crank levers 71, one individual to each of the T-levers 18. The springs 73, which are individual to each of the bell cranks 71, are connected to a rod 74 which is secured to the frame of the machine. The upper ends of the bell cranks 71 are formed with a lug or hook 76 extending rightwardly therefrom, as may be observed in Fig. 4. Each of these hooks are adjacent the leftward end of the associated T-lever 18.

Upon any of the T-levers 18 being selected, and thus being depressed as a result thereof, an associated bell crank 71 will be pivoted about rod 72 in a clockwise direction by means of its individual spring 73, its hooked end 76 thereby moving over the leftward extremity of the T-lever 18 and preventing its immediate return upward. Thus, the T-lever 18 will be held in its selected or depressed position.

The result of the T-levers 18 being locked in their depressed positions results in their connected rearwardly extending levers 22 being held in their extreme clockwise direction, as viewed in Fig. 2, which results in the interponents 27 being maintained in their upward position adjacent the individual punches 29. Thus, the interponents 27 will be held in their selected position for a length of time equal to the time that the T-levers 18 are locked in their depressed positions.

At the same time that the T-levers 18 were depressed and the bell crank 71 was rotated in a clockwise manner, as viewed in Fig. 4, to lock the T-levers in their selected position, a universal T-lever 18 caused the electrical contact 28 to close, thus establishing an electrical circuit for the energization of the solenoid 52. As previously mentioned, upon the energization of solenoid 52, the operating lever 44 is pivoted in a clockwise direction, as viewed in Fig. 1, resulting in the punch hammer 37 being moved forwardly to engage the selected interponents 27. At the same time that the operating lever 44 is pivoted by the bell crank 49 the bell crank likewise imparts movement to the rod 56. Movement of the rod 56 is imparted to the link 57, resulting in the link 57 moving downwardly, as viewed in Fig. 2. Inasmuch as the lower extremity of link 57 has a slot 77 therein, no motion will be imparted to the bell crank lever 58 until such time as the lever 57 has been moved a distance equal to the length of the slot. The slot 77 has been so positioned in respect to the link 57 and bell crank 58 as to insure that the operating lever 44 will cause its upwardly extending lug 53 and set screw 54 to engage the punch hammer 37 to cause the latter to engage the punch interponents before such time as the link 57 imparts motion to the bell crank 58. Inasmuch as the bell crank 58 is pivoted at 59, a counterclockwise motion will be imparted thereto, as viewed in Fig. 2, resulting in the link 62 being moved rightwardly (Fig. 2). Referring now to Fig. 1, clockwise motion will be imparted from link 62 to bell crank 63 about pivot 64 resulting in link 66 being moved toward the left. As link 66 moves toward the left, as viewed in Fig. 1, or toward the right as viewed in Fig. 4, bell crank 67 will be pivoted in a counterclockwise

direction (Fig. 4) about rod 68 resulting in a counterclockwise movement to the ball 69. Ball 69 then engages the bell cranks 71 which had moved into locking position, thereby moving them in a counterclockwise direction, as viewed in Fig. 4, thus releasing the hooks 16 from the T-levers 18. The T-levers 18 therefore are now free to resume their normal or upward positions. Inasmuch as a certain timing has been provided by means of slot 71 in lever 51 and the use of set screws it has been assured that the T-levers will not be released until the interponents 27 have been positively engaged by the punch head 31.

Fig. 1 shows other details in the operating mechanism of a Wheatstone perforator, principally a device for effecting the variable feed of the tape. However, inasmuch as this device is not a part of the invention nor is its operation necessary in order to understand the operation of the invention, its description is not deemed necessary. However, in the event that the operation and details of the variable tape feed device are of interest, a complete understanding may be gained by referring to the above-mentioned Kleinschmidt patent or "Teletype" Bulletin No. 125.

Although a specific embodiment of the invention has been shown and described, it will be understood that this embodiment is but illustrative and that various modifications may be made therein without departing from the scope and spirit of this invention.

What is claimed is:

1. In a keyboard perforator, a plurality of punches, a plurality of interponents, one individual to each of said punches, a plurality of T-levers, one individual to each of said interponents, connecting levers between said interponents and said T-levers, key lever means for selectively conditioning said interponents through said T-levers and said connecting levers, a punch hammer for moving said conditioned interponents to cause said punches to perforate a tape, and latch means individually associated with each of said T-levers for locking said T-levers in their selected positions whereby said interponents are held in their said selected positions after said key lever means are released.

2. In a keyboard perforator, a plurality of punches, a plurality of interponents, one individual to each of said punches, a plurality of T-levers, one individual to each of said interponents, connecting levers between said interponents and said T-levers, key lever means for selectively conditioning said interponents through said T-levers and said connecting levers, a punch hammer for moving said conditioned interponents to cause said punches to perforate a tape, latch means individually associated with each of said T-levers for locking said T-levers in their selected positions whereby said interponents are held in their said selected positions after said key lever means are released, and release means for restoring said latch means whereby said T-levers are released to move from their selected positions.

3. In a keyboard perforator, a plurality of punches, a plurality of interponents, one individual to each of said punches, a plurality of T-levers, one individual to each of said interponents, connecting levers between said interponents and said T-levers, key lever means for selectively conditioning said interponents through said T-levers and said connecting levers, a punch

hammer for moving said conditioned interponents to cause said punches to perforate a tape, latch means individually associated with each of said T-levers for locking said T-levers in their selected positions whereby said interponents are held in their selected positions after said key lever means are released, and release means common to said individual latch means for restoring said latch means whereby said T-levers are released to move from their selected positions.

4. In a keyboard perforator, a plurality of punches, a plurality of interponents, one individual to each of said punches, a plurality of T-levers, one individual to each of said interponents, connecting levers between said interponents and said T-levers, key lever means for selectively conditioning said interponents through said T-levers and said connecting levers, means for moving said conditioned interponents to cause said punches to perforate a tape, latch means individually associated with each of said T-levers for locking said key levers in their selected positions whereby said interponents are held in their said selected positions, and means under the control of said interponent moving means to restore said latch means whereby said T-levers are released to move from their selected positions.

5. In a perforating machine, a key actuated selector, a plurality of punches, a plurality of punch interponents, one individual to each of said punches, means under the control of said selector for selectively conditioning said punch interponents, means for moving said punch interponents to cause said punches to perforate a tape, and latch means for locking said selected interponent conditioning means only whereby said punch interponents are held in their said selected positions after said selector is released.

6. In a perforating machine, a key actuated selector, a plurality of punches, a plurality of punch interponents one individual to each of said punches, means under the control of said selector for selectively conditioning said punch interponents, means for moving said punch interponents to cause said punches to perforate a tape, latch means for locking said selected interponent conditioning means only whereby said punch interponents are held in their said selected position after said selector is released, and release means for restoring said latch means whereby said interponent conditioning means are released.

7. In a perforating machine, a key actuated selector, a plurality of punches, a plurality of punch interponents, one individual to each of said punches, means under the control of said selector for selectively conditioning said punch interponents, means for moving said punch interponents to cause said punches to perforate a tape, latch means for locking said interponent conditioning means whereby said punch interponents are held in their said selected positions after said selector is released, and release means directly under the control of said punch interponent moving means for restoring said latch means whereby said interponent conditioning means are released.

8. In a perforating machine, a key actuated selector, a plurality of punches, a plurality of punch interponents, one individual to each of said punches, means under the control of said selector for selectively conditioning said punch interponents, means for moving said punch interponents to cause said punches to perforate a tape, latch means for locking said interponent

conditioning means whereby said punch interponents are held in their said selected positions after said selector is released, and release means directly under the control of and operating during the latter part of the cycle of operation of said punch interponent moving means for restoring said latch means whereby said interponent conditioning means are released.

9. In a perforating machine, a key actuated selector, a plurality of punches, a plurality of punch interponents, one individual to each of said punches, means under the control of said selector for selectively conditioning said punch interponents, means for moving said punch interponents to cause said punches to perforate a tape, latch means equal in number to the number of said plurality of punch interponent conditioning means and operating substantially simultaneously with the operation of said selector whereby said punch interponents are held in their said selected positions after said selector is released, and release means common to said individual latch means for restoring said latch means whereby said interponent conditioning means are released.

10. In a keyboard perforator, a plurality of punches, a plurality of interponents, one individual to each of said punches, key lever means for selectively conditioning said interponents, a punch hammer for moving said conditioned interponents to cause said punches to perforate a tape, and latch means associated with each of said interponents for maintaining said interponents in their selected positions only after said key lever means are released.

11. In a perforating machine, a key actuated selector, a plurality of punches, a plurality of punch interponents, one individual to each of said punches, said interponents selectively conditioned by said selector, a return spring for each of said interponents, means for moving said conditioned punch interponents to cause said punches to perforate a tape, means to block said interponents in their conditioned position, and means under control of said punch interponent moving means to restore said blocking means whereby said punch interponents may be returned by their said springs to their nonconditioned positions.

12. In a keyboard perforator, a plurality of punches, a plurality of interponents, one individual to each of said punches, key lever means for selectively conditioning said interponents, means for moving said conditioned interponents to cause said punches to perforate a tape, latch means individually associated with said interponents for holding said interponents in their said selected positions after said key lever means are released, and means directly under the control of said means for moving said interponents for releasing said interponents from their said selected positions.

13. In a keyboard perforator, a plurality of punches, a plurality of interponents, one individual to each of said punches, key lever means for

selectively conditioning said interponents, a punch hammer for moving said conditioned interponents to cause said punches to perforate a tape, latch means individually associated with said interponents for holding said interponents in their selected positions after said key lever means are released operating substantially simultaneously with the operation of said key lever means, and release means for restoring said latch means whereby said interponents are free to resume their nonselected positions.

14. In a keyboard perforator, a plurality of punches, a plurality of interponents, one individual to each of said punches, key lever means for selectively conditioning said interponents, a solenoid energized upon the operation of said key lever means, a punch hammer under the control of said solenoid for moving said conditioned interponents to cause said punches to perforate a tape upon the energization of said solenoid, latch means individually associated with said interponents for holding said interponents in their selected positions after said key lever means are released, and means directly under the control of said solenoid for releasing said latch means whereby said interponents are released from their said selected positions.

15. In a keyboard perforator, a plurality of punches, a plurality of interponents, one individual to each of said punches, key lever means for selectively conditioning said interponents, a solenoid energized upon the operation of said key lever means, a punch hammer under the control of said solenoid for moving said conditioned interponents to cause said punches to perforate a tape upon the energization of said solenoid, latch means individually associated with said interponents for holding said interponents in their selected positions after said key lever means are released, and a release bail common to said individual latch means and directly under the control of said solenoid for releasing said latch means whereby said interponents are released from their said selected positions.

16. In a keyboard perforator, a plurality of punches, a plurality of interponents, one individual to each of said punches, key lever means for selectively conditioning said interponents, a solenoid energized upon the operation of said key lever means, a punch hammer under the control of said solenoid for moving said conditioned interponents to cause said punches to perforate a tape upon the energization of said solenoid, latch means individually associated with said interponents for holding said interponents in their selected positions after said key lever means are released, a release bail common to said latch means for releasing said latch means, and a linkage system extending between said release bail and said solenoid and directly under the control of said solenoid for operating said release bail whereby said interponents are released from their said selected positions.

CLARENCE J. RUSSNAK.
